COATING DEVICE

Frank P. Carlson, Astoria, N. Y.

Application July 21, 1933, Serial No. 681,459

18 Claims. (Cl. 91—50)

This invention relates to devices for uniformly applying a coating substance simultaneously to both faces of a work piece and to the method by means of which the coating operation is effectively accomplished.

Certain kinds of work require, for various reasons, to be coated either wholly or in part at both of its surfaces in such a way that the coating substance is not only uniformly distributed over the areas required to be covered, but that such coating is neither interrupted nor incomplete at any spot or at the start or finish of the coated area. The application of superimposed covering-coatings is frequently used in printed work, where, for instance, over certain printed areas a metallic or water-proofing layer is added. In the manufacture of labels and posters intended to be applied to show-windows, mirrors, etc. from either within or without, or designed to be wrapped around containers, with either of its printed faces exposed, the marginal edges of the work are preferably provided with an adhesive border for facilitating their attachment.

Irrespective of the purpose for which the coated work may be intended, the application of the coating should be uniform in thickness, the coating should be thin and evenly distributed over the coated area, clear of all blemish in the form of sediment, small particles or the like, and the coated surface must have no uncovered or "bald" spots, usually due to uneven distribution of the coating substance and to gripping of the work at its ends for the purpose of feeding it through existing devices of similar nature. A uniform and uninterrupted application of a coating substance to the work results in not only highly economic and speedy production, but also in very satisfactory results as to the practical use of the finished work and its ultimate pleasing appearance, not to mention other advantages incidental to the method employed, as will become presently evident.

Although the application of coating substances to printed work is an old art, the heretofore employed methods and devices are not only limited as to their usefulness, but produce often unsatisfactory work at a comparatively high cost. I now refer particularly to the manufacture of labels, posters and the like, provided with marginal adhesive areas for their attachment. Up to the present, such articles were first printed and then their edges were supplied with a cement or gum at one face of

the sheet. Eventually an adhesive was applied to the other face of the work after the first applied gum became sufficiently dry to allow the coating on the reverse side. Due to the unevenness of the application and due to the successive drying, the edges of the work will curl, thereby seriously interfering with the "stacking up" of the work. The curling requires another operation, known as "breaking", consisting of forcibly flattening out of the gummed edges, whereby the dried adhesive surface is broken. This is usually done by hand.

Another important defect is found in heretofore used methods of edge-gumming, also due to the unevenness, or rather the thickness of the applied adhesive. When the coating of gum is relatively thick, although it may be far thinner than the work itself, and the work is stacked-up in the usual way, the edges will pile up much higher than the portions between the edges, rendering it impossible to stack-up the finished work to commercially practical heights.

The present method and device have for their objects to overcome all of the aforementioned disadvantages, to simplify and materially reduce the cost and time of production, and to effect commercially practical, finished articles which are neat in appearance, which will not curl and which may be piled up into sufficiently high stacks to produce a marked saving in space in the shop, while at the same time effecting a large saving in handling and shipping of the finished work.

These and still further important objects of my invention will become more clearly evident from the following description and the accompanying diagrammatical drawing, adapted to serve for explanatory purposes only and not intended to in any way limit my invention to the actual showing.

In the drawing, Figure 1 is a plan view of the left-hand portion of my device, considered from the direction of advance of the work.

Figure 2 is an elevation in partial cross-section of Fig. 1.

Figure 3 is a diagrammatical developed plan view of a typical carrier arrangement of my device.

Figure 4 is a plan view of a work-piece coated at its side edges, and

Figure 5 is an end view thereof, in exaggerated proportions.

Referring now to the figures, numeral 10 denotes the left-hand portion of a feeder platform, 55

which may be adjusted to accommodate work of any desired width. Such adjustability is indicated by arrow I. The table or platform 10 is provided with a marginal edge 11 for guiding the work fed into the machine. A work-feeder in the form of endless, parallelly disposed belt conveyors travels with its upper runs 12 over the top surface of the feeder platform and is intended to convey the work-pieces, for instance, 10 sheets of either printed or unprinted paper, to the coating mechanism. The sheets are preferably held down against the upper conveyor surfaces by either a suction device or by resilient fingers or arms, which arrangements are not shown for the sake of clearness of the drawing.

The coating mechanism of my device consists of a reservoir for holding the coating substance, such as glue, cement, metallic mixtures, shellac or any other desired coating material or adhesive. The reservoir comprises a container 13, open at the top, in which the coating substance 14 is preferably kept at a constant level. Partially immersed into the coating material and mounted on a shaft 15 in fixed bearings is the primary coating-supplying and coating-applying carrier 16, in the form of a metal cylinder 17, provided with a hub 18 and an outer, resilient work-engaging layer 19.

In contacting engagement with primary carrier 16 is the primary coating distributor 20, mounted upon floating shaft 21, which is adjustably supported by arm 22 from stationary shaft or pins 23. The purpose of the floating suspension of distributor 20 is to render it adjustable, so that it may be forcibly held against carrier 16 and adjusted to any desired degree of pressure, in the manner indicated by the arrow over arm 22.

Superimposed above and in intimate, adjustable contact with primary carrier 16, is a secondary carrier 24, consisting of a metallic, cylindrical body 25, provided with hub 26, and covered with a work-engaging, resilient rim 27. This carrier is mounted on floating shaft 28, supported by adjustable arm 29, which latter is pivoted at fixed points 30. Due to its floating suspension, secondary carrier 24 is adjustable relative to the primary carrier, as indicated by arrows over arm 29, and may be caused to bear thereagainst at any desired degree by means of a spring arrangement, adjusting screws or other suitable means, not shown.

In contacting engagement with the secondary carrier 24 are two sets of rotary and oscillating secondary distributors 31 and 32, mounted, respectively, on shafts 33 and 34 in pairs, only one of each pair being shown in the drawing. At the ends of shafts 33 and 34 are provided collars 35 and 36 engaged by a centrally pivoted arm 37, adapted to impart by its swinging operation, indicated by arrows, an oscillating motion to the revolving secondary distributors. The shafts of these distributors are lodged in adjustable bearings, not shown, so as to facilitate the positioning of rolls 31 and 32 in proper or desired relation to the work-engaging surfaces of the secondary coating carriers. Such possible adjustment towards or from the carriers, as indicated by arrows II in Fig. 2, is of far reaching importance in respect to the amount and quality of the coating applied to the upper surface of the work, as will be explained later on in this specification.

I prefer to construct these cylinders from metal, however any other suitable, relatively

non-resilient material may be employed. The same applies to the construction of the primary distributor 20 and the interior bodies of both carriers, which are made of either metal or other suitable relatively non-elastic matter. When rust-producing adhesive is used in the device, I prefer to employ aluminum for the primary distributor 21 and for the interior parts 17 and 25 of conveyors 16 and 24 respectively. The oscillating secondary distributors are made of brass.

Attention is called to the attachment of all rolls to their respective shafts. Instead of the usual key-way and key, I employ set-screws in the hubs of the rolls throughout, since I have found that the slightest unbalancing of the shafts or rolls causes a hardly perceptible vibration of the rotary mechanisms, which however is sufficient to cause readily distinguishable marks of uneven distribution of the applied coating.

At the right-hand portions of Figures 1 and 2 and in rear of the carriers, a plurality of double conveyors for the coated work is provided, each consisting of lower and upper endless belts 38 and 39, adapted to contact with their respective inner runs, both of which are adapted to move simultaneously in the direction outward or from the carriers.

Disposed above work-feeding conveyors 12 and 20 conveyors 38, and arranged in spaces between these conveyor arrangements, there is provided a work-straightening means, consisting of sprockets or wheels indicated at 40 and 41, mounted in pairs or in greater numbers on shafts 42 and 43. Sprocket chains 44 connect the sprocket wheels, and support work-stops 45, which are in exact alignment over the entire width of the machine, and are designed to move into the path of the work, as may be seen at 45 in Fig. 2.

Forming a continuation of double conveyors 38 and 39 are delivery rolls 46 mounted to shaft 47 and designed to assist the transfer of the coated work to drying conveyor 48, operating within drier 49, from which latter the finished work is eventually discharged.

The illustration of Figures 1 and 2 represent, as stated previously, only the left-hand portion of my device, the width of which depends upon the size of work to be handled. Its right-hand portion, a symmetrical counterpart of what is shown, is to be visualized and is to be considered to complete the structure and to contain the driving mechanism of the device, which latter is intended to forcibly actuate the various rotary parts and conveyors in the desired directions indicated and at the desired speeds.

Referring to Fig. 3 the primary carrier 16 is illustrated at the centre between the primary distributor 20 at its left and the secondary carrier 24 at its right. It will be observed from this figure that the width of the distributor is slightly greater than that of the primary carrier, and that the width of the latter exceeds the width of the secondary carrier. Such arrangement of these rotors is by no means arbitrary and came about through extensive practical experiments in the effort to obtain a uniform, never varying coating of a desired thinness at both faces of the work, without heavier side margins, streaks of other blemish. In this figure there will also be observed the correct position of the wiper 50, which bears against the inner faces 20' and 16' of the primary distribu-

tor and the primary carrier at their contacting areas. The wiper is designed to scrape off excessive coating substance elevated by the primary carrier and kept partially rolling down by the primary distributor, thereby reverting such excess back into pan or container 13.

Attention is also called to the relative positions of rolls 16 and 24. It will be noted that two sides or edges of these rolls are substantially flush with one another (the upper edges of the rolls shown in Fig. 3), whereas the other lower edge of roll 16 extends substantially beyond the other lower edge of roll 24.

Inasmuch as the work to be coated passes over the coinciding (upper) edges of the rolls, but does not travel over more than a relatively small portion of the width of the rolls, the unused parts of the rolls' surfaces will carry up a sufficient quantity of coating material to the secondary reciprocating distributors 31 and 32, so as to fully cover the applying surface of roll 24 for an adequate coating operation of the upper face of the work. The fact that that area of roll 16 which extends beyond the lower edge of roll 24 carries up an extra supply of the coating material, which is unaffected by the contact between rolls 16 and 24, a transfer of that extra coating material is made to the off-set face of roll 24, thereby augmenting the required supply of the coating material carried up by the contacting portions of the roll surfaces.

From the foregoing it becomes clearly evident that the simultaneously accomplished coating operation at top and bottom of the work entirely depends upon the simultaneous transfer of the coating material from one roll to the other, while the application of the coating upon the work is taking place.

In Figures 4 and 5 are illustrated typical samples of the finished work. Numeral 51 indicates a sheet of either printed or unprinted paper, the upper face 52 of which represents its so-called finished face, while 53 indicates the rough or unfinished face thereof. At the side edges of the sheet are provided upper coatings 54 and lower coatings 55 of even width, thickness and uniformity, without a fault, "bald spots" or "left-out" at ends of the coating areas, so often to be observed in similar work produced heretofore.

Operation

In Figures 1 and 2 numerous arrows are marked at or near the different parts of the machine, indicating directions of movements. Thus on hub 15 of primary carrier 16 is an arrow indicating that the latter revolves clockwise, while the secondary carrier moves in opposite direction as is the case with primary distributor 20, whereas oscillating secondary distributors 31 and 32 rotate clockwise. The upper run 12 of the work-feeder moves towards, and the adjacent runs of conveyors 38 and 39 travel away from the coating mechanism. The upper run of the work-straightening means advances to the left, while its lower run travels to the right.

All of the shafts of the various parts of the machine are positively or forcibly driven so that there may not occur any slippage or lost motion between any of the moving units. The surface speeds of all parts is alike, except that of the work-feeder-runs 12, which move at an increased speed, indicated by double arrows III in Figures 1 and 2.

As a sheet is placed upon upper runs 12 of the

work-feeder, it is conveyed towards the coating mechanism until its forward or leading edge comes in contact with blocks or work-stops 45 (or 45) on the bottom run of chain 44, which latter moves at the same speed as the coating rolls. The sheet, held down against the upper runs 12 of the work-feeder is continuously urged against the work stops by each of the runs 12 individually, so that its leading edge, before reaching the carriers is brought into parallel position with the carrier shafts. This is due to the exact alignment of all the work-stops carried by the chains of the work-straightening arrangement.

The primary carrier elevates a quantity of the coating from the reservoir, which coating is uniformly distributed over that carrier by primary distributor 20, while the surplus coating substance is scraped off from the inner faces of the two rolls by wiper 50 and diverted back into the reservoir. The sides of the sheet, indicated in broken lines in Figures 1 and 2, are directed between the two carriers in such a way that the latter grip the sheet only at an area near their respective inner edges. Thus only a portion of the work-engaging or work surfaces of the carriers is employed for applying a coating to the sheet, while the rest of their work-surfaces are utilized for the transfer of the coating substance from the primary to the secondary carrier.

Before the upper or secondary carrier can effectively coat the upper surface of the sheet, the coating substance transferred from the area of the primary carrier, which is unaffected by the coating of the lower sheet surface, must be brought back to the edge area. In other words the transferred coating of the secondary carrier must be spread and evenly distributed over the entire work-surface of the upper carrier. Such distribution is effected by the oscillation of the secondary distributors 31 and 32.

The correct coating of the two surfaces of the sheet greatly depends upon the structure of the sheet material, its upper, so-called finished and its lower, unfinished surface, for the reason that the latter much more readily absorbs the coating, and therefore requires a more generous supply, while the upper surface resists the penetration of the coating, consequently demanding a lesser supply. When after absorption of the moisture contained in the coating, the latter dries upon both faces of the sheet and the layers proved to have different thicknesses, the edges of the sheet will curl up towards the thicker layer. Such would be the case when the secondary carrier becomes over-supplied with coating material. By increasing or decreasing the contact pressure between the secondary distributors and the upper carrier, or by altering the degree of oscillation of the distributors, the supply of the coating substance reaching the upper sheet surface is regulated.

When the coated sheet leaves the carriers, it is conveyed between the adjacent runs of conveyors 38 and 39 and over rolls 46 to an electric drying device consisting of a heat-proof belt conveyor 48, operating in casing 49, from which latter the finished work is discharged for handling in the usual way.

In the foregoing description certain terms were employed. In order to prevent any misunderstandings, be it known that the word "speed" indicates surface speed, "carriers" designate rotors supplying and applying a coating

substance and "distributors" indicate coating distributing means. The latter constitute some of the most essential parts of my device and must be capable of a minute manual and subsequent self-adjustment to deliver uniformly applied coatings.

In recapitulation of the above described invention, its salient features may be compassed as follows: A controlled, continuous supply of coating substance, pre-distributed over the work-engaging faces and applied simultaneously in thin layers to both surfaces of the work, the unfinished or more porous surface receiving its coating from a portion of the work-engaging surface of the primary carrier, the remaining surface transferring the coating substance to the secondary carrier, from a portion of the work-engaging surface of the primary carrier, the remaining surface transferring the coating substance to the secondary carrier; from a portion of the latter's work-surface the upper face of the sheet receives the coating, but not before the latter is evenly distributed over the entire work surface of the upper carrier.

While I have shown and described specific forms of my device and the method followed to produce the desired results, it is quite evident that my invention is capable of a great many modifications, whereby entire surfaces or other parts than edges of sheets may be simultaneously coated at both faces, thereby saving many handling operations and producing a well finished article of uniform quality and appearance at a much lesser cost than possible up to now.

By the same token, my device may be employed for applying but a single face coating to certain work. Obviously I shall not be limited to exactly the subject matter disclosed, but reserve for myself the right to make changes and improvements in, and to employ my invention for allied purposes within the broad scope of the following claims.

I claim:

1. In a coating device, the combination with a single supply source, of a plurality of coating carriers adapted to simultaneously coat both faces of the work, means in cooperation with one of the carriers for evenly distributing the coating thereover, without permitting an undue accumulation thereon, and the sides thereof, of a surplus of the coating, and means in operative engagement with another carrier for evenly distributing thereover the coating prior to applying it to the work.

2. In a coating device for simultaneously, uniformly and uninterruptedly applying a coating to both faces of the work, a plurality of rotary coating carriers in cooperation with one another, one of the carriers adapted to both supply the coating and to apply the same at one face of the work, another carrier adapted to apply the coating at the other face of the work, said supply-carrier adapted to transfer the coating to the other carrier, and means operatively coordinated to the latter carrier for evenly distributing its transferred coating before applying same to the other face of the work.

3. In a coating device for simultaneously, uniformly and uninterruptedly applying a coating to both faces of the work, a combination coating-supplying and coating-applying primary carrier, a coating-applying secondary carrier, both carriers being rotatably mounted and adapted to revolve in opposite directions towards one another, a single supply reservoir

disposed below said primary carrier, the latter adapted to be partially submerged in and to elevate the coating from within the reservoir, a rotary distributing member in cooperation with said primary carrier, wiper means in engagement with said distributing member and said primary carrier, coating distributing means in operative coordination with said secondary carrier, the primary carrier adapted to coat one face of the work, the secondary carrier adapted to coat simultaneously the other face of the work after its coating has passed said coating distributing means.

4. In a coating device for the purpose described, a single coating supply container, a primary coating supplying and applying carrier partially immersed in the coating substance of the container, an adjustably mounted coating-distributing member in operative engagement with and wider than said primary carrier, a wiper engaging the extending edges of said member and the receding edges of said primary carrier, an adjustably mounted secondary carrier superimposed above and narrower than said primary carrier, both carriers being rotatable and adapted to revolve at equal speed in opposite directions toward one another, and oscillating rotary coating-distributing means adjustably mounted relative to, in cooperation with, and considerably wider than said secondary carrier.

5. The combination with a coating device, as set forth in claim 4, of work feeding means, adapted to operate at a speed higher than that of said carriers, a conveyor for the coated work, adapted to operate at the speed of said carriers, and work delivering means adjacent to said conveyor, adapted to also operate at the speed of the carriers.

6. The combination with a coating device, as set forth in claim 4, a delivery or work feeding means disposed ahead of said carriers and adapted to operate at a higher speed than the latter, work straightening means disposed above said work feeding means and adapted to operate at the speed of said carriers, a delivery conveyor and work discharge means arranged, respectively, in front and rear of said carriers and adapted to operate at the speed of the latter.

7. In a device for coating simultaneously both faces of the work, a coating container, a primary coating carrier partially immersed in the coating substance of the container and adapted to elevate the coating and apply the same to one face of the work, an adjustably mounted rotary distributor in forcible engagement with said primary carrier, wiping means contacting with said primary carrier and the distributor, an adjustably mounted secondary carrier in forcible engagement with said primary carrier and superimposed thereabove, adjustably mounted, rotary oscillating distributing means in forcible engagement with said secondary carrier, said carriers, said distributor and said distributing means operating at an equal surface speed, a work feeder disposed ahead of said carriers and operating at a higher speed than the carriers, a delivery conveyor and work discharge means operating at the speed of said carriers, and work straightening means in cooperation with said work feed, operating at the speed of said carriers, the width of said distributor for the primary carrier being greater than that of the primary carrier, the width of

- the latter being greater than that of the secondary carrier.
8. In a device for the purpose described the combination with a single supply source, of a primary carrier, a rotary distributor in cooperation therewith and a secondary carrier superimposed above and in constant operative engagement with said primary carrier, the width of the distributor being greater than that of the primary carrier, the width of the latter being greater than that of the secondary carrier.
9. In a device for the purpose described the combination with a single supply source, of a primary coating-supplying and coating-applying carrier rotary mounted in fixed bearings, a secondary coating-supplying and coating-applying carrier in cooperation with and narrower than the former, mounted in floating bearings and adapted to operate under forcible contact with the primary carrier, both carriers provided with resilient working surfaces, a substantially nonresilient primary distributor in cooperation with and wider than said primary carrier, lodged in floating bearings and adapted to constantly and forcibly bear against said primary carrier, wiping means in engagement with the latter and said primary distributor, substantially non-resilient secondary distributing means oscillatingly and rotatably mounted, and adapted to be adjustable relative to and in engagement with the secondary carrier, and being considerably wider than the latter, said carriers, distributor and distributing means adapted to operate at equal surface speeds, work-feeding means arranged ahead of the carriers and adapted to operate at an increased surface speed, and conveying means for the coated work, disposed in rear of the carriers and adapted to operate at the surface speed of the carriers.
10. In a device as set forth in claim 9, said carriers comprising metallic rolls provided with resilient, work-engaging surfaces.
11. In a device as set forth in claim 9, means in cooperation with said work-feeding means for straightening the work fed to said carriers, prior to being engaged by them.
12. In a device for simultaneously and uniformly coating two edges at both faces of a sheet, a pair of primary coating-supplying and coating-applying carriers mounted on a common shaft, lodged in fixed bearings, coating supply reservoirs so disposed beneath the primary carriers that they are partially immersed in the coating, a primary distributor for each carrier, mounted on a common floating shaft and adapted to be adjustable relative to, and in desired forcible contact with said carriers, said distributors arranged above the coating substance of the reservoirs, a pair of secondary coating-supplying and applying carriers, mounted on a common shaft in floating bearings, and superimposed above and in contacting engagement with the primary carriers, the secondary carriers adapted to be adjustable as to pressure exerted by them against the primary carriers, two pairs of oscillating and rotatable secondary distributors in cooperation with the secondary carriers and superimposed above them, each corresponding pair mounted on a common shaft in adjustable bearings, the latter adapted to facilitate any desired adjustment of the secondary distributors towards or from said secondary carriers, thereby varying the contact pressure, controlling the distribution of the coating over the surfaces of the carriers, said primary and secondary carriers and their respective distributors adapted to operate at an equal surface speed, and wiper means in engagement with the inner surfaces of the primary carriers and the primary distributors.
13. In a device, as set forth in claim 12, a work-feeder disposed ahead of said carriers and adapted to operate at a greater speed than the carriers, a work-straightening means in cooperation with said work-feeder, adapted to operate at the speed of the carriers, and comprising a pair of bands or chains provided with a plurality of aligned work-stops, the latter adapted to coordinate the progress of the work relative to the speed of the carriers, in between which the work is fed, endless conveyors disposed in rear of the carriers, adapted to operate at the latter's speed and to convey the coated work from the carriers, work-delivery means forming the continuation of said conveyors and operating at the same speed as the latter, and means adjacent to said delivery means for drying the coated work.
14. In a device of the class described, the combination with a single supply source, of a plurality of primary coating-supplying and applying carriers, a plurality of secondary carriers, rotary primary distributors extending with both of their ends beyond both sides of, and being in cooperation with the primary carriers, rotary and reciprocating secondary distributors co-acting with the secondary carriers, all said carriers and distributors operating forcibly at the same speed, said carriers comprising metal rolls provided with resilient work surfaces, said distributors comprising metal cylinders in contact with the work surfaces of said carriers.
15. In a device as set forth in claim 14, the width of the primary distributors exceeding those of the work surfaces of the primary carriers, the width of the latter exceeding that of the secondary carriers, and said secondary distributors having a width substantially exceeding that of the secondary carriers, one of the faces of each cooperating primary and secondary carrier substantially coinciding with one another, while the other face of each secondary carrier is off-set relative to the corresponding face of the primary carrier.
16. In a coating device, a single source of supply or well, a primary coating carrier partially extending into said well, means in cooperation with and controlling and evenly distributing the amount of coating material carried by the primary carrier, the latter adapted to directly apply one portion of the coating material to one face of the work, a secondary carrier in operative engagement with said primary carrier and adapted to take up the other portion of the coating material from said primary carrier, means operatively associated with said secondary carrier for evenly distributing over the latter's work surface the taken-up portion of the coating material prior to applying it to the opposite face of the work.
17. Means for simultaneously and uniformly coating both faces of relatively soft and pliable work, in the form of individual sheets, comprising a single supply of coating material, means for individually feeding the sheet work in a continuous succession, means for elevating a portion of the coating material and evenly distributing that portion to a film of uniform thinness, means for applying a part of the film to one face of the work, means for trans-

- 5 ferring another part of the film to the opposite side of the work, means for moving the transferred film part to a position from which the desired portion of the other face of the work 10 is to be coated, and means for evenly redistributing the transferred and moved film part before its application to the work, and means for applying that other film part in its even, redistributed condition to the opposite face of 15 the work.
18. Means for simultaneously applying uniformly predistributed coating films to both faces of relatively soft and pliable work in individual sheet-form from a single supply of coating material, comprising a single coating supply, means for moving in a continuous succession individual sheets of work, means for elevating from the

supply a portion of the coating material, primary means for distributing the coating uniformly, before its application, to constitute a relatively thin, even film, said elevating means designed to apply one part of said even film directly to one face of the individual sheets of work, operative means for transferring another part of said film from said elevating means beyond the other side of the work, and means in cooperation with said operative transferring means, for evenly redistributing and simultaneously moving the transferred film part, prior to its application, into the path of the work, and for applying the redistributed and moved film part to the opposite work face. 15

FRANK P. CARLSON.
